UNITED STATES PATENT OFFICE

2,615,601

SHIRT FORM WITH COLLAR STRIP LOCK

Lawrence M. Kahn, New York, N. Y.

Application July 14, 1950, Serial No. 173,712

4 Claims. (Cl. 223—71)

1

This invention relates to new and useful improvements in shirt forms with collar strip locks.

More particularly, the invention proposes a shirt form provided with a collar tab portion engageable into the back portion of the collar of a shirt mounted on the shirt form. A collar strip is provided for engaging through the collar to hold it in shape, and upright, and a novel lock is associated with the collar tab and the collar strip in order to assist in holding the collar strip in position.

The new and novel lock, in accordance with this invention, comprises a single upwardly directed tongue on the collar tab portion formed by a slot cut in the collar tab portion and cooperative with a single downwardly directed tongue on the center of the back portion of the collar strip engaging downwards through the slot in the collar tab portion in order that said upwardly directed tongue will be in face contact with said downwardly directed tongue to firmly hold the collar strip in position.

Another object of the invention is the construction of a device as described which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure—

Fig. 1 is a plan view of a shirt form with a collar strip lock constructed in accordance with this invention.

Fig. 2 is a fragmentary sectional view taken on the line 2—2 of Fig. 1.

Fig. 3 is a fragmentary view of a portion of Fig. 1 showing the collar tab portion, per se.

Fig. 4 is a fragmentary view of the central portion of the collar strip illustrated, per se.

Fig. 5 is a back view of a shirt form with a collar strip lock constructed in accordance with this invention and illustrated with a shirt mounted in position thereon.

The shirt form with a collar lock, in accordance with this invention, comprises a shirt form 10 having a body portion 11 upon which a shirt 12 with an attached collar 13 may be mounted. The shirt form 10 is also provided with a collar tab portion 14 positioned upwardly of the body portion 11 in order to hold the attached collar 13 in an upright position. The collar tab portion

2

14 is adapted to engage into the back portion of said collar 13. A collar strip 15 is provided for engaging inside of the collar 13 to hold the collar 13 upright. This collar strip 15 is adapted to extend around the back of the collar, and its end portions are adapted to extend around the front of the collar terminating at the front collar opening. Collar support strips of this type are generally known in the art and further explanation of its position will not be given in this specification.

A single upwardly directed tongue 16 is formed in said collar tab portion 14 by an arcuate slot 17 which is cut in said collar tab portion 14. A single downwardly directed tongue 18 is formed on the center of the back portion of said collar strip 15 and is adapted to engage downwardly through the slot 17 in order that said upwardly directed tongue 16 will be in face contact with said downwardly directed tongue 18, as clearly illustrated in Fig. 2 for holding said collar strip 15 in position.

The downwardly directed tongue 18 is of sufficient length so that its bottom edge rests upon the body portion 11 of the shirt form 10, as clearly illustrated in Figs. 1 and 2. The downwardly directed tongue 18 is formed by slits 20 extending upwards from the bottom edge of said collar strip 15. The downwardly directed tongue 18 is formed with a rounded bottom end 21. The bottom portions of the slits 20 which connect with the bottom edge of the collar strip 15 are formed with rounded corners 22. These rounded corners 22 assist in mounting the collar strip 15 in position on the collar tab portion 14.

The specific details of the shirt form 10 will not be given in this specification as they form no part of the invention. The invention itself resides in the locking means for connecting the collar strip 15 with the collar tab portion 14.

The operation and use of the new shirt form with the collar strip lock may be understood from the following:

The shirt 12 is mounted upon the shirt form 10 in the usual way. The tab portion 14 is engaged into the back portion of the attached collar 13. The collar strip 15 is extended through the collar 13 of the shirt and then the collar strip 15 and collar tab 14 are connected as follows. The upwardly directed tongue 16 is pushed backwards and simultaneously the downward directed tongue 18 is engaged through the slot 17. The rounded corners 22 facilitate the engagement of the downwardly directed tongue 18 into the slit 17 because they free the rounded bottom end

21 of the tongue 18 which then may easily engage into the top of the slit 17. The tongue 18 is pushed all the way down until its bottom end rests on the body portion 11 of the shirt form 10. The collar 13 of the shirt 12 will now be supported in an upright position.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:

1. A shirt form with a collar strip lock, comprising a shirt form having a body portion upon which a shirt with an attached collar may be mounted and a collar tab portion positioned upwardly to said body portion, said collar tab portion being engageable into the back portion of said collar of said shirt, a collar strip for engaging inside of said collar to hold said collar upright, a single upwardly directed tongue on said collar tab portion formed by a slot cut in said collar tab portion, a single downwardly directed tongue on the center of the back portion of said collar strip engaging downwards through said slot

5 in order that said upwardly directed tongue will be in face contact with said downwardly directed tongue to firmly hold said collar strip in position.

2. A shirt form with a collar strip lock as defined in claim 1, in which said downwardly directed tongue has its bottom tip rested on said body portion.

10 3. A shirt form with a collar strip lock as defined in claim 1, in which said downwardly directed tongue is formed by slits extending upwards from the bottom edge of said collar strip.

15 4. A shirt form with a collar strip lock as defined in claim 1, in which said downwardly directed tongue is formed by slits extending upwards from the bottom edge of said collar strip, the bottom of said tongue being round, and the corners of said slits in said collar strip being also round.

20 25 LAWRENCE M. KAHN.
